HEADBOARD FOR A BED

William Joseph Carr, Gardner, Mass., assignor to Heywood-Wakefield Company, Gardner, Mass., a corporation of Massachusetts

Filed Mar. 25, 1964, Ser. No. 79,173

Term of patent 14 years

(Cl. D5—4)

FIG. 2

FIG. 1 is a front view of the headboard, the rear side of said headboard being the same in appearance as the front side thereof;

FIG. 2 is a side view of the headboard, the other side of said headboard being the same in appearance as the side illustrated.

I claim:

The ornamental design for a headboard for a bed, as shown and described.
